CHILD'S CAR CHAIR

Bobby L. Smith and Jean Smith, both of 737 Midland Ave., Manhattan, Kans.

Filed Apr. 3, 1961, Ser. No. 64,570

Term of patent 14 years

(Cl. D15—1)

The dominant features of our design reside in those portions shown in full lines on the drawings.

We claim:

The ornamental design for a child's car chair, substantially as shown and described.
